LOW FREQUENCY INDUCTION FURNACE

Ludwig Dreyfus, Västerås, Sweden, assignor to Allmänna Svenska Elektriska Aktiebolaget, Västerås, Sweden, a corporation of Sweden

Application November 19, 1956, Serial No. 622,911

Claims priority, application Sweden November 22, 1955

2 Claims. (Cl. 219—10.75)

Induction heating furnaces with cylindric coils are often used for partial heating of the ends of bars or for heating cuttings or billets along their whole length. The heating coil thereat has always an axial length somewhat larger than the length of the work-piece to be heated to full temperature. In high frequency furnaces having equal winding density it is obtained thereby that the work-piece is practically heated uniformly over the whole length (heating of billets), or over the desired partial length (bar heating).

As in the last years the low frequency furnace with 50 or 60 cycles for thorough heating of large, magnetic billets to the Curie point has gained ground, the same structural feature of the furnace coil has been adopted with projecting ends and equal current density along the coil. But it was found that in low frequency furnaces of this type the free ends of the charge always will be colder than the middle portion thereof. It is the purpose of the present invention to over-come this inconvenience.

The invention will be described with reference to the accompanying drawing, in which Fig. 1 shows a coil having a main portion and two projecting portions, and Figs. 2a and 2b show wiring diagrams.

For the understanding of the invention it is necessary first to show why the low frequency furnace and the high frequency furnace are different in the above mentioned respect, for example in heating billets. Considering Fig. 1, in which the main portion of the coil is designated by *a* and the two projecting portions by *b* and *b'*, respectively, the iron core by *c*, and the billet by *d*, the following will be evident.

If the ends of the billet shall be just as warm as its middle portion, the flux ϕ of the coil at the end of the billet (ϕ_b) has to be the same as in the middle of the billet (ϕ_m), but only under the assumption that a flux $\phi_b = \phi_m$ enters axially already at the end faces of the billet, and just the projecting winding portions outside the length of the billet have to generate that flux. The flux ϕ_m of the coil, however, consists of two components, viz. the flux ϕ_{my} on the surface of the billet including the depth of penetration and the eddy flux $\phi_{m\sigma}$ outside, between the billet and the coil. $\phi_{m\sigma}$ is always in phase agreement with the current I_m of the coil. ϕ_{my} , however, is about 54° later than $\phi_{m\sigma}$ and I_m . The phase angle of the resulting flux $\phi = \phi_{my} + \phi_m$ depends on whether the flux ϕ_{my} or the flux $\phi_{m\sigma}$ predominates.

In this respect, however, the high frequency furnace and the low frequency furnace work differently. In the high frequency furnace leaving a small depth of penetration ϕ_{my} is much smaller than $\phi_{m\sigma}$, and therefore $\phi_{m\sigma}$ determines generally the phase angle of the resulting flux ϕ_m . Thus it is approximately in phase with the current I_m of the coil, and of course the flux ϕ_b of the projecting winding portions is in phase with the current I_b of these portions, which current has hitherto been identical with I_m . In high frequency furnaces, therefore, ϕ_m and ϕ_b have approximately the same phase angle, and

if the turns N_b of the projecting winding portions are made sufficiently large, also ϕ_b may have the same value as ϕ_m with the result that the billet is heated uniformly along its entire length.

5 The low frequency furnace works quite differently. The flux of the billet ϕ_{my} is much larger than the eddy flux $\phi_{m\sigma}$ due to the much greater depth of penetration of the field. It is therefore ϕ_{my} which generally determines the resulting phase angle of the flux, and it is delayed beyond 45° with respect to I_m , while the flux ϕ_b of the projecting winding portions still is in phase with I_b . If now, as always, the current I_b is made equal to I_m by series connection of all the winding portions, ϕ_m will be about 45° later than ϕ_b and the condition for uniform heating, i. e. ϕ_b equal to and in phase with ϕ_m , cannot at all be fulfilled.

20 According to the present invention, this difficulty is overcome in a simple manner. The coil is divided by additional taps into different winding sections, i. e. the main section having N_a series connected turns, which cover the length of the billet or generally speaking the length of the charge to be heated, and into one or two projecting sections at the ends of the coil outside the heating length of the charge, this section having N_b or (and) N'_b turns.

25 Phase agreement of the associated flux ϕ_m and ϕ_b and ϕ'_b respectively, is obtained in a simple way by applying to these winding sections voltages E_a , E_b and E'_b respectively, which are in phase agreement to each other. If further, the winding factors of the individual sections are defined by

$$E_a = \omega N_a f_a \phi_m 10^{-8}$$

$$E_b = \omega N_b f_b \phi_b 10^{-8}$$

$$E'_b = \omega N'_b f'_b \phi'_b 10^{-8}$$

30 the condition $\phi_m = \phi_b = \phi'_b$ for uniform heating is fulfilled according to the equations for dimensioning

$$40 \quad \frac{E_a}{N_a f_a} = \frac{E_b}{N_b f_b} = \frac{E'_b}{N'_b f'_b}$$

For the reduction in practice it is sufficient to evaluate

$$45 \quad f_a \approx 1 \quad f_b = f'_b \approx 0.86$$

At billet heating, N_b is made N'_b and both sections are suitably series-connected and fed with a voltage

$$50 \quad \frac{E_a}{N_a f_a} = \frac{E_b + E'_b}{(N_b + N'_b) f_b}$$

55 The voltages required for the execution of the invention may be obtained in different manners. E_a and $E_b + E'_b$ may be taken from a transformer with a transformation ratio $E_a/E_b + E'_b$. These voltages are applied in parallel to the corresponding winding sections. Such a transformer, a so called voltage divider is shown in Fig. 2a. Also a three windings transformer, having two secondary windings may be used from which the winding sections N_a and $N_b + N'_b$ are fed, as shown in Fig. 2b.

60 What I claim is:

65 1. Low frequency induction furnace comprising a cylindrical coil energized by a single-phase alternating source, at least one of the ends of said coil projecting beyond the length of the charge to be heated characterised in that the coil is divided by additional taps into a main section comprising N_a turns and covering the length of the charge to be heated and one projecting section comprising N_b turns for bar heating, and two projecting sections N_b and N'_b for billet heating and in that the main section and the projecting sections are fed separately by

voltages E_a and E_b and E'_b respectively in phase agreement of such values that

$$\frac{E_b}{N_b f_b} = \frac{E_a}{N_a f_a} = \frac{E'_b}{N'_b f'_b}$$

wherein f is the winding factor of the sections.

2. Low frequency induction furnace according to claim 1 having two projecting sections N_b and N'_b char-

acterised in that these sections are series-connected and fed with one voltage only (Fig. 2a and 2b).
